UNITED STATES PATENT OFFICE

RALPH B. GOODRICH, OF CINCINNATI, OHIO, ASSIGNOR TO THE EAGLE MANUFACTURING COMPANY, OF CINCINNATI, OHIO, A CORPORATION OF OHIO.

OPERATING MECHANISM FOR WASHING AND WRINGING MACHINES.

1,075,413.

Specification of Letters Patent.

Patented Oct. 14, 1913.

Application filed September 23, 1909. Serial No. 519,125.

To all whom it may concern:

Be it known that I, RALPH B. GOODRICH, a citizen of the United States, residing at Cincinnati, in the county of Hamilton and State of Ohio, have invented certain new and useful Improvements in Operating Mechanism for Washing and Wringing Machines, of which the following is a specification.

10 The present invention relates to motor-operated washing and wringing apparatus, and the primary object is to provide simple and effective mechanism, which will permit a single motor to drive the washing means 15 or agitator and the wringer, the one being given an oscillatory movement, and the other a continuous rotary movement.

A further and important object is to provide a mechanism, which will automatically 20 connect the motor and agitating means when the cover of the washing machine is closed, and simultaneously disconnect the motor and wringer, and will, when the cover is opened, disconnect the motor from the 25 agitator, while automatically connecting the motor with the wringer. As a result, the apparatus is peculiarly adapted for household purposes, inasmuch as a person wholly unacquainted with machinery or 30 mechanics can successfully use the same.

Still a further and important object is to so house and guard all the moving parts that danger of injuring the same or the operator or the clothing being operated 35 upon, is entirely eliminated.

A preferred embodiment of the invention is illustrated in the accompanying drawings, wherein:—

Figure 1 is a perspective view of the same, 40 with the cover in closed position. Fig. 2 is a perspective view, showing the cover open. Fig. 3 is a detail elevation, partially in section, illustrating the driving mechanism. Fig. 4 is a top plan view thereof. 45 Fig. 5 is a detail sectional view illustrating the gearing that connects the motor-driving shaft with the agitator. Fig. 6 is a detail sectional view through the mechanism for transforming the oscillatory movement of the driving shaft into rotary movement. Figs. 7 and 8 are respectively sectional views looking in opposite directions 50 through the ratchet mechanism and associated gearing.

55 In the embodiment disclosed the tub or

receptacle for the clothing to be washed, is designated 10, and is preferably supported upon legs or standards 11. The tub or receptacle has a top, comprising a stationary section 12 and a movable portion 13, the latter being connected to the stationary portion by hinges 14 provided with stop lugs 15 that limit the opening or outward swinging movement of the cover portion 13, and relieve the weight thereof from the part of the apparatus co-operating therewith.

A base or bed 16 is fixed upon the stationary portion 12 of the cover, and carries at one end a bracket 17 to which is rigidly secured a motor 18 preferably of the oscillatory type. This motor, in the preferred embodiment of the invention, is of the form disclosed in a patent granted to me on April 14, 1908, No. 884,654, and needs no detailed 75 explanation beyond the statement that it comprises a casing 19, within which operates an oscillatory piston 20 carried by a shaft 21 that is extended as shown at 22 to form a driving shaft. The shaft 22 is journaled in suitable boxes 23, and carries at one end a beveled driving gear 24.

Fixed upon the swinging cover 13 is a combined bracket and housing 25, in which is journaled the upright shaft 26 of an agitator 27 that may be of any desired character. The upper part of the shaft 26 is inclosed in a globular casing 28, into which projects one end of the countershaft 29, said countershaft being connected with the 90 shaft 26 by intermeshing beveled gears 30. The outer end of the shaft 29 extends beneath a protecting hood 31, and carries a beveled gear 32 that meshes with the driving gear 24 when the cover is lowered and 95 closed, but lifts out of mesh with said driving gear when the cover is raised.

From the above, it will be obvious that if the motor 18 is in operation and the cover 100 13 is closed, the agitator will be given an oscillatory movement through the gearing described, but when the cover is thrown to open position, then the agitator will be automatically disconnected from the motor. In order to shroud or shield the driving gear 24 105 when the cover is raised, a movable semicircular hood or guard 33 is employed that is hinged, as shown at 34, so that it may swing to and from a position over the gear 24. This hood has pivoted thereto, one end 110

of a link 35, the other end of said link, as shown in Fig. 4, being pivoted at 36 to the cover. Thus, when the cover swings to open position, the hood 33 will be swung over the beveled gear 24, and when said cover is closed, the hood swings away from the beveled gear, permitting the gear 32 to move into mesh therewith.

Mounted upright on the base or bed 16 is 10 a wringer, comprising a frame 37 having coacting wringer rolls 38 that are suitably geared together, as shown at 39, and also preferably provided with a handle crank 40, which may be readily removed. Disposed in 15 line with the shaft of the lower roll 38, is a wringer driving shaft 41 that can be connected to and disconnected from said wringer roll shaft by means of coöperating toothed clutch members 42, 42^a, one being fast to the lower 20 roll spindle or shaft, the other rotating with the shaft 41, and being slidable along the same. Its sliding movement is effected by means of a lever 43 fulcrumed upon a supporting arm 44, and having a yoke 45 that embraces the clutch member 42^a and engages in an annular groove 46 formed therein. Springs 47, connected to the yoke 45 and to a stationary part of the frame, may be used to normally maintain the clutch members 30 disengaged, but it will be obvious that if the lever 43 is swung against the action of the springs, the clutch members will be brought into coaction, and the wringer driving shaft 41 thus coupled to the wringer rolls. This operation may be accomplished 35 by hand, but it is also effected automatically. To this end, the lever 43 is provided with an offset tappet lug or projection 48 that is disposed in the path of movement of the 40 swinging cover 13 or a fixed element 48^a thereon. It will therefore be obvious that when this cover is swung to open position and when as a consequence, the agitator is disconnected from the motor, the wringer driving shaft 41 will be coupled to the wringer driving shaft 41. On the other hand, when the cover 45 45 moves to closed position, the springs 47 can react to disconnect the wringer driving shaft 41 from the wringer rolls, while the 50 agitator will be connected to the motor shaft.

The above described wringer driving shaft 41 is given a continuous rotary movement from the motor-driving shaft 22, preferably by the following mechanism. Loosely journaled upon the motor driving shaft 22 are two freely rotatable cupped ratchet wheels 49, 49^a, arranged in reversed but matching relation to form a casing, each wheel having similar internal ratchet teeth 50. Secured to the driving shaft 22, within the casing thus produced, is a hub 51 carrying oppositely disposed arms 52, on which are pivoted dogs 53 that respectively and 65 alternately operate on the ratchet teeth 50

of the wheels 49, 49^a. It will thus be obvious that when the motor is in operation, and the shaft 22 rotating back and forth upon its axis, the ratchet wheels 49 and 49^a will be alternately given a step-by-step rotation in 70 opposite directions. The said ratchet wheels 49 and 49^a, are respectively provided with gear wheels 54 and 55, preferably, though not necessarily formed, integral therewith, and one of these gear wheels, as 54, meshes 75 directly with another gear wheel 56 fast upon the wringer driving shaft 41. The other gear wheel 55 on the ratchet wheel 49^a meshes with an idler 57, which, in turn, meshes with a gear wheel 58 fast upon the wringer driving shaft 41. Consequently, it 80 will be clear that the oscillation of the motor driving shaft 22 will effect a continuous rotary movement of the drive shaft 41 in one direction, and when this shaft is coupled to the wringer, the rolls will be given a 85 continuous rotary movement.

From the above, it will be seen that a simple but thoroughly practical apparatus is provided, which can be successfully used in 90 the household by one wholly unacquainted with machinery or mechanics. All that an operator has to do is to connect the motor with the water supply, and thus set the same in operation. Having introduced the clothes 95 to be cleaned into the receptacle, the cover is closed, and thereupon the agitator is connected to the motor, and is thus placed in operation, while the wringer is at a standstill. Having completed the cleansing operation, the cover is raised, whereupon the agitator is disconnected from the motor and the gear 24 automatically shrouded or covered. The opening movement of the cover 100 couples the wringer to the motor so that the clothes can be taken from the machine and 105 passed through the wringer rolls.

From the foregoing, it is thought that the construction, operation and many advantages of the herein described invention will 110 be apparent to those skilled in the art, without further description, and it will be understood that various changes in the size, shape, proportion and minor details of construction may be resorted to without departing 115 from the spirit or sacrificing any of the advantages of the invention.

Having thus fully described my invention, what I claim as new, and desire to secure by Letters Patent, is:

1. In operating mechanism of the character described, the combination with an oscillatory driven member, of a rotary driven member, an oscillatory motor, gearing connecting the motor with the oscillatory driven member, and gearing connecting the motor with the rotary driven member, said latter gearing including means for transforming oscillatory motion to rotary motion.

2. In operating mechanism of the character

ter described, the combination with an oscillatory driven member, of a rotary driven member, an oscillatory motor, gearing connecting the motor with the oscillatory driven member, gearing connecting the motor with the rotary driven member, said latter gearing including means for transforming oscillatory motion to rotary motion, and means for alternately connecting the rotary driven member and oscillatory member to, and disconnecting them from, the motor.

3. In operating mechanism of the character described, the combination with an oscillatory motor having a driving shaft, of an oscillatory driven member geared to the shaft, ratchet wheels journaled on the driving shaft, dogs mounted on the shaft and alternately acting on the ratchet wheels, and a rotary driven member geared to and continuously receiving motion from the ratchet wheels.

4. In operating mechanism of the character described, the combination with a base and a movable element associated therewith, of a driven member mounted on the movable element, a motor mounted on the base and detachably engaged gears connecting the motor and driven member and carried respectively by the base and movable element, said gears automatically disengaging when the movable element is moved.

5. In operating mechanism of the character described, the combination with a base, a movable element carried thereby, of a motor, a driven member, and means automatically operated by the movable element to effect the connection and disconnection of the motor and driven member.

6. In operating mechanism of the character described, the combination with a base and a movable element carried thereby, of a motor, a driven member, and means automatically operated by the movable element when the same is moved to connect the motor and driven member.

7. In operating mechanism of the character described, the combination with a base and a movable element carried thereby, of a motor, a driven member, a clutch for connecting and disconnecting the motor and driven member, and clutch operating means including an element located in the path of movement of the movable element.

8. In operating mechanism of the character described, the combination with a base having a movable element associated therewith, of a motor, and a driven member, both mounted on the base, a clutch for connecting and disconnecting the motor and driven member, and a lever for operating the clutch, said lever having a portion disposed in the path of movement of the movable element.

9. In operating mechanism of the character described, the combination with a base

and a movable element carried thereby, of an oscillatory driven member, a rotary driven member, a motor for driving the members and means automatically operated on the movement of the movable element to different positions for alternately connecting the motor to the oscillatory member and to the rotary member.

10. In operating mechanism of the character described, the combination with a base having a movable element associated therewith, of an oscillatory driven member, a rotary driven member, a motor for operating the members, and means automatically operated on the movement of the movable element to one position to disconnect the motor and oscillatory member and connect the motor to the rotary member, said means being automatically operated on the movement of the movable element to another position to disconnect the motor and rotary member, and connect said motor and oscillatory member.

11. In operating mechanism of the character described, the combination with a base having a movable element associated therewith, of an oscillatory driven member carried by the movable element, a gear connected with said driven member, a motor including a driving shaft, a gear carried by the driving shaft, the gear of the oscillatory driven member being movable into and out of mesh with the gear of the motor on the movement of the movable element, a rotary driven member, a clutch for connecting and disconnecting the motor and rotary driven member, and clutch actuating means disposed in the path of movement of the movable element.

12. In operating mechanism of the character described, the combination with a base, of a movable element associated therewith, an oscillatory driven member carried by the movable element, a gear connected with said driven member, an oscillating motor including a driving shaft, a gear carried by the driving shaft, the gear of the oscillatory driven member being movable into and out of mesh with the gear of the driving shaft on the movement of the movable element, a rotary driven member, means mounted on the driving shaft and geared to the rotary driven member for transforming the oscillating motion of the driving shaft into rotary motion for said rotary driven member, a clutch for connecting and disconnecting the rotary driven member from the said means, and a clutch operating lever having a portion disposed in the path of movement of the movable element.

13. In a gearing, the combination with a base, of a movable element associated therewith, a motor including a driving shaft, a gear carried by the driving shaft, a driven member mounted on the movable element, a

4
gear carried with said driven member and movable into and out of mesh with the gear of the driving shaft, and a guard for the driving shaft gear that is movable over such gear when the movable element is moved to a position for disengaging the said gears.

14. In a gearing, the combination with a base, of a movable element associated therewith, a motor mounted on the base and 10 having a driving shaft, a gear carried by the driving shaft, a driven member supported in the movable element, a gear carried with the driven member and movable into and out of mesh with the gear of the 15 driving shaft, a guard for the driving shaft gear pivotally mounted on the base and movable to and from a position over said gear, and a link connection between the guard and the movable element.
15. In operating mechanism of the character described, the combination with a base having a movable element associated therewith, of a driven member carried by the movable element, a combined gear bracket 20 and housing mounted on the movable element, gearing for the driven member carried by said bracket and housing, and a motor mechanism having a gear engaged

and disengaged by the gearing of the driven member according to the position of the 30 movable element.

16. In a gearing, the combination of a support, a hinged member, a vertical oscillating shaft journaled in the hinged member, a gear on the outer end of the shaft, 35 a rotary driven member, a single motor, a driving shaft connected with said motor and supported in a plane above the hinged member, gear devices operatively connected with said shaft 40 for operating said oscillating shaft and said rotary driven member, and arranged to permit the driving connection for the oscillating shaft to be shifted when the hinged member is raised, and a device comprising 45 means for controlling said gear devices for selecting either the oscillating motion or the rotary motion.

In testimony whereof I hereunto affix my signature in the presence of two wit- 50 nesses.

RALPH B. GOODRICH.
